UNITED STATES PATENT OFFICE.

MARK B. KERR, OF ROSEBANK, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed May 5, 1924. Serial No. 711,040.

This invention relates to telephone exchange systems, and more especially to such systems as employ automatic switches in the establishment and completion of talking connections.

In multi-office telephone systems, it is the usual practice to provide two wire trunks extending between the several exchanges. In effect, these interoffice trunks appear in contacts of so-called office selector switches at the calling office, and terminate in contacts of incoming selector switches at called offices. When one of these trunks is seized for the purpose of extending a calling line, provision is made for rendering it non-selectable at the calling office. When connection has been completed over such a trunk to a called line at a distant office, provision is also made for allowing both the calling and called subscribers to control the release of the said trunk. The invention is particularly applicable to such systems wherein the number of interoffice incoming selector switches is less than the number of final selector switches and wherein the called subscriber has supervision over the release of the incoming trunk.

Accordingly, it is the object of the invention to increase the efficiency of interoffice communication by allowing the release of an interoffice trunk to be controlled by a called subscriber, with means for automatically and immediately releasing such trunk independently of the called subscriber, when the trunk is seized for the extension of a second calling line prior to disconnection by the said called subscriber.

A feature of the invention relates to the means for rendering an interoffice trunk selectable for the purpose of completing a second conversational connection thereover before the complete release of a preceding first conversational connection.

Another feature relates to an interoffice incoming selector trunk which has an automatic timed release feature combined with an immediate release feature, the latter being effective when the said incoming selector is seized for the purpose of extending a second calling line prior to disconnection by the previously called line.

Other inherent features and advantages may be ascertained after a consideration of the following detailed description of the

operation of a particular application of the invention.

While for the purpose of description it has been chosen to illustrate the invention as applied to an automatic telephone system wherein switches of the coordinate type are used, such as shown in the patent to C. L. Goodrum and J. N. Reynolds, No. 1,515,735 granted Nov. 18, 1924, it is understood that the invention in its broad aspects is not to be limited thereby. The invention may be as well applied to so called power drive systems and, in general, to any automatic telephone system employing markers and wherein the selectable condition of an inter-office trunk is dependent upon disconnection by a called party.

The invention is described in connection with a telephone system such as disclosed in the copending application of Warren W. Carpenter, Serial No. 703,362, filed April 1, 1924.

Detailed description.

Let it be assumed that the subscriber at station 101, whose telephone line is located in office 100, has initiated a call for the purpose of conversing with the subscriber at station 121, whose line is located in a distant office. In the manner described in detail in the patent to S. B. Williams and E. S. Gibson, No. 1,543,967 granted June 30, 1925, the calling line 102 is extended by means of automatic switches in office 100 to an idle interoffice trunk such as 108, the latter being immediately rendered non-selectable at the office selector switch to other calling lines. The seizure of trunk 108 causes the operation of slow release relay 111 in a circuit traceable from battery through its left winding, upper armature and back contact of relay 128, upper left winding of repeating coil 121, tip conductor of the trunk, through apparatus in office 100, returning over the ringside of the trunk, through the left lower winding of repeating coil 121, lower inner armature and back contact of relay 128 to ground through the right winding of relay 111. Relay 111

extends ground through the upper inner armature and back contact of relay 103, left armature and contact of relay 111, left normal contacts of relay 123, sender selector start wire 122 to battery through the wind-

ing of relay 112. The operation of relay 112 causes the actuation of sender selector switch 110 to selectively associate an idle incoming sender as 120 with the interoffice trunk. For the manner in which relay 112 causes the operation of switch 110, reference may be had to the patent to S. B. Williams and E. S. Gibson No. 1,543,967 granted June 30, 1925, and herein before referred to. As soon as an idle sender has been connected, relay 103 operates, opening the circuit of relay 111 which releases. The tip and ring conductors of the incoming trunk are now extended to the receiving mechanism in the sender 120, and the sender at office 100 transmits series of characteristic impulses to cause the called line designation to be recorded on the registers of sender 120. When relay 103 operated, ground was removed from the start wire 122, and an obvious circuit was closed for the holding relay 123. The operation of relay 123 opens the sender selector starting circuit at a second point to prevent subsequent reoperation of relay 103, after completion of connection through switches 170 and 180. Relay 123 also connects ground through its right armature and contact, right normal contacts of relay 132 to the sleeve conductor of trunk 104. When the designation of the called line has been recorded in sender 120, connector 130 is actuated to connect the controlling marker 140 to the sender. The marker 140 now functions to control the selective operation of incoming switch 170 and final switch 180 so as to connect trunk 104 with the called line 190. For a detailed description of the manner in which these latter operations are effected, reference may be had to the application of Warren W. Carpenter, Serial No. 703,362, filed April 1, 1924.

When the foregoing connection of trunk 104 and line 190 has been completed the sender selector switch 110, sender 120, connector 130, marker 140, and the various connectors 150, 160, etc., are released and revert to common use. The release of the sender selector switch 110 causes the release of relay 103, thus completing connection of the interoffice trunk 108 with the left windings of repeating coil 121, causing reoperation of relay 111. Relay 123 being slow to release does not retract its armatures during the interval between the release of relay 103 and the operation of relay 111. As soon as relay 111 reoperates, it provides a locking circuit for relay 123. This circuit may be traced from battery through the winding of relay 123, lower inner armature and contact of relay 103, left outer armature and contact of relay 129, left armature and front contact of relay 123, left armature and contact of relay 111 to ground at the upper inner armature and contact of relay 103. The reop-

eration of relay 111 also extends this same ground over conductor 154, conductor 152, armature and contact of relay 126, lower inner armature and contact of relay 125 to battery through the winding of ringing control relay 124. This ground is also extended by means of conductor 154 through the winding of relay 125 which does not operate at this time since its winding is shunted. The operation of relay 124 connects current from the ringing source 153 through the winding of relay 126, right armature and contact of relay 124, lower outer armature and contact of relay 125, ring conductor of trunk 104, contacts of switch 170, ring conductor of trunk 105, contacts of switch 180, through the ringing apparatus at the called subscriber's station and returning thence through contacts of switch 180, tip conductor of trunk 105, contacts of switch 170, tip conductor of trunk 104, upper outer armature and contact of relay 125, to generator ground at the left armature of relay 124. When the subscriber at station 121 removes the receiver from the switchhook the resistance of the above traced circuit through the winding of relay 126 is reduced, and this relay operates. Relay 126 at its armature and contact removes the shunt from the winding of relay 125 which now operates to the grounded conductor 154, thus extending the tip and ring conductors of trunk 104 to the right windings of repeating coil 121 and operating supervisory relay 127. Relay 127 closes an obvious operating circuit for relay 128 which reverses the current in the conductors of the interoffice trunk, thus serving as an indication to the sender in office 100 that the called subscriber has answered. When the conversation is terminated and the calling subscriber replaces the receiver upon the switchhook, relay 111 releases. The release of relay 111 removes ground from the conductor 154, but if the called subscriber has not meanwhile replaced the receiver, relay 125 remains operated in a circuit traceable from battery through its winding, conductor 154, winding of relay 129, left normal contacts of relay 132 to ground at the lower armature and contact of relay 128. Relay 129 operates in this circuit and at its right inner armature and contact maintains a busy potential on the sleeve conductor of trunk 104. When interrupter 161 closes its lower contact, ground is connected through the right outer armature and contact of relay 129, left normal contacts of relay 131 to battery through the winding of the same. Relay 131 locks through its winding and locking contact to ground at the right inner armature of relay 129. Should the called subscriber maintain the receiver off the switchhook indefinitely, the circuits are so arranged that after a predetermined interval regulated by the time of closure of the upper

contact of interrupter 161, the trunk 104, switches 170, 180 and associated apparatus are automatically released. When therefore interrupter 161 closes its upper contact, assuming that the called subscriber still has the receiver off the switchhook, ground is connected through the right armature and contact of relay 131 to battery through the winding of release relay 132. Relay 132 10 locks through its winding, left armature and front contact to ground at the lower armature and contact of relay 128. Relay 132 at its left normal contacts opens the circuit for relays 129 and 125. These latter relays 15 now release. Relay 125 severs the tip and ring conductors of the incoming selector trunk, and relay 129 removes holding ground from the sleeve conductor. In the manner described in the above mentioned application 20 of Warren W. Carpenter, Serial No. 703,362, filed April 1, 1924, removal of ground from the sleeve conductor of trunk 104 causes the release of the connection through switches 170 and 180. This severance of the 25 connection causes the release of relay 127 which in turn causes the release of relay 128. The connection has thus been completely restored to normal following the closure of the upper contact of interrupter 161. From the 30 foregoing description, it will be seen that provision is made for automatically releasing, after a definite interval an interoffice incoming selector when the called party fails to disconnect following the termination of 35 conversation.

Assume that a connection has been completed by means of trunk 108 to called line 190, and after the termination of conversation, the party at station 121 fails to replace the receiver upon the switchhook within the predetermined time. Under these conditions, should the trunk 108 be again seized by a selector switch in the office 100 during the interval between disconnection of a previous 40 calling party and the closure of the upper contact of interrupter 161, the incoming selector will be immediately disconnected from the previous called line and rendered available in extension of the second calling line. 45 In this case, relays 111, 125, 127, 128 and 129 are operated. When therefore trunk 108 is seized by an office selector at this time, relay 111 will operate as hereinbefore described. The operation of relay 111 closes a 50 circuit for release relay 132 which may be traced from battery through the winding thereof, left inner armature and contact of relay 129, left armature and contact of relay 111 to ground at the upper inner armature and contact of relay 103. The operation of 55 relay 132 brings about the successive release of relays 125, 129, 127, 128 and switches 170, as before described. Thus, the incoming selector is immediately rendered selectable by 60 a second calling line, even though the pre-

vious called party has failed to replace the receiver within the specified time.

What is claimed is:

1. In a telephone exchange system, a calling office, a called office, lines in said calling office, lines in said called office, a two-wire trunk for completing connections between lines in said calling office and lines in said called office, means at said called office for maintaining said trunk in engagement with a called line after said trunk has been disengaged from the calling line, and means under control of said calling office for disengaging said trunk from said called line after said trunk has been disengaged from said calling line. 70

2. In a telephone exchange system, a calling office, a called office, lines in said calling office, lines in said called office, a two-wire trunk for completing connections between lines in said calling office and lines in said called office, means at said called office for maintaining said trunk in engagement with a called line after said trunk has been disengaged from the calling line, and means located in said called office under control of said calling office for disengaging said trunk from said called line after said trunk has been disengaged from said calling line. 85

3. In a telephone exchange system, calling lines, called lines, a two-wire trunk extending between said calling and said called lines, means for completing a connection from one of said calling lines over said trunk to a particular one of said called lines, means under control of said called line for maintaining said called line in engagement with said trunk, and means responsive to the extension of a second calling line to said trunk prior to disconnection of said called line 90 therefrom to cause a forced disconnection of said called line to immediately allow said trunk to be used in completing the connection of said second calling line to another or the same particular called line. 100

4. In a telephone exchange system, calling lines, called lines, a selector trunk for extending one of said calling lines to a particular one of said called lines, means for preventing said selector trunk from completing other talking connections while either said calling or said called line is connected thereto, and means effective upon disconnection of said one of the calling lines and responsive to the extension of another of said calling lines prior to disconnection of said called line for causing a forced disconnection of said called line to thereby allow said trunk to extend said other calling line. 115

5. In a telephone exchange system, calling lines, called lines, a selector trunk for extending one of said calling lines to a particular one of said called lines, means for preventing said selector trunk from completing other talking connections while either 125

- said calling or said called line is connected thereto, means for forcing a release of said selector trunk when said calling line disconnects prior to disconnection by said called line, a timing arrangement for timing the actuation of said forcing means, and means effective upon a second seizure of said selector trunk prior to disconnection by said called line for rendering said timing arrangement ineffective and for causing an immediate forced release of said selector trunk.
6. In a telephone exchange system, calling lines, called lines, a selector switch for extending one of said calling lines to a particular one of said called lines, means for preventing said selector switch from releasing while either said calling or said called line is connected thereto, means for forcing a release of said selector switch when said calling line disconnects prior to disconnection by said called line, a timing arrangement for timing the actuation of said forcing means, and means effective upon a second seizure of said selector switch prior to disconnection by said called line for rendering said timing arrangement ineffective and for causing an immediate forced release of said selector switch.
7. In a telephone exchange system, calling lines, called lines, a two-wire trunk for extending one of said calling lines to a particular one of said called lines, means for preventing said trunk from completing other talking connections while either said calling or said called line is connected thereto, means for forcing a release of said trunk when said calling line disconnects prior to disconnection by said called line, a timing arrangement for timing the actuation of said forcing means, and means effective upon a second seizure of said trunk prior to disconnection by said called line for rendering said timing arrangement ineffective and for causing an immediate forced release of said trunk.
8. In a telephone exchange system, a calling line, a called line, a selector trunk for extending said calling line to said called line, a timing arrangement associative with said trunk, means responsive to disconnection by said calling line prior to disconnection by said called line for rendering said timing arrangement effective to cause a forced disconnection of said called line from said selector trunk, and means effective upon a second seizure of said selector trunk prior to disconnection by said called line for causing an immediate forced disconnection of said called line from said selector trunk.
9. In a telephone exchange system, a calling line, a called line, a selector switch for extending said calling line to said called line, a timing arrangement associative with said switch, means responsive to disconnection by said calling line prior to disconnection by said called line for rendering said timing arrangement effective to cause a forced disconnection of said called line from said selector switch prior to disconnection by said called line for causing an immediate forced disconnection of said called line from said selector switch.
10. In a telephone exchange system, a calling line, a called line, a selector trunk for completing connections between said calling line and said called lines, a timing arrangement associative with said selector trunk, means responsive to disconnection by said calling line prior to disconnection by said called line for rendering said timing arrangement effective to cause a forced release of said selector trunk, and means effective when said selector trunk is seized a second time prior to disconnection by said called line for causing an immediate release of said selector trunk.
11. In a telephone exchange system, a calling line, a called line, a two-wire trunk for completing connections between said calling line and said called lines, a timing arrangement associated with said two-wire trunk, means responsive to disconnection by said calling line prior to disconnection by said called line for rendering said timing arrangement effective to cause a forced release of said two-wire trunk, and means effective when said two-wire trunk is seized a second time prior to disconnection by said called line for causing an immediate release of said two-wire trunk.

In witness whereof, I hereunto subscribe my name this 29th day of April, A. D. 1924.

MARK B. KERR.
